UNITED STATES PATENT OFFICE.

MAURICE GILLETTE, OF NEW YORK, N. Y.

DESIGN FOR A STORE-FRONT.

54,908.

Specification for Design.

Patented Apr. 20, 1920.

Application filed October 23, 1919. Serial No. 332,837. Term of patent 7 years.

To all whom it may concern:

Be it known that I, MAURICE GILLETTE, a citizen of the United States of America, residing at New York city, county and State of New York, have invented a new, original, and ornamental Design for a Store-Front, of which the following is a specification, reference being had to the accompanying drawing, forming part hereof, which illustrates a front view, in perspective, of a store-front embodying my new design.

I claim:—

The ornamental design for a store front, as shown.

Signed at New York city, New York, this 16th day of October, 1919.

MAURICE GILLETTE.
